UNITED STATES PATENT OFFICE

BARTHOLOMEW H. GREENE, OF SEBRING, OHIO

BURNING RACK

Application filed May 18, 1927. Serial No. 192,182.

The invention relates to racks for supporting plates, dishes and similar porcelain or china ware and the like in a saggar, for burning or baking in a kiln. The saggar is a box or case of hard clay or the like, usually made so the bottom of one forms the cover of the next, thus protecting the articles within from smoke, and the irregularities of heat and the like.

10 It is usual practice in burning plates and similar articles to place the same on the edge within the saggar, the lower edges of the plates resting upon spaced triangular bars loosely positioned upon the bottom of the saggar.

The weight of the plates resting on these separate bars often causes the bars to move laterally, permitting a portion of the edge of the plate to contact with the bottom of the saggar, and since it is customary to place a layer of sand on the bottom of the saggar, the edges of the green plates frequently contact with this sand causing the same to be burned into the plate and ruining the same.

25 The object of the present invention is to provide a rack arranged to be placed upon the sand in the bottom of the saggar to support the plates in the ordinary position, this rack being so arranged and constructed that it is impossible for the edge of the plate to contact with the sand.

The above and other objects may be attained by providing a rack of such size and shape that the edge portion of each plate will have only one or two point contacts with the rack; the lower side of the rack being provided with one or more ribs arranged to be imbedded in the sand upon the bottom of the saggar to prevent lateral movement of the rack within the saggar.

An embodiment of the invention thus set forth is illustrated in the accompanying drawing, in which

45 Figure 1 is a fragmentary longitudinal sectional view through a portion of a saggar, showing the improved burning rack in position to support a row of plates;

50 Fig. 2, a transverse sectional view through the same;

Fig. 3, a fragmentary perspective view of a portion of the improved burning rack, and

Fig. 4, a similar view of a different form of the rack.

Similar numerals of reference indicate corresponding parts throughout the drawing.

The saggar 1 may be of any usual and well known construction, being in the form of a box arranged to be closed at its top by placing another saggar thereon as illustrated in Figs. 1 and 2.

A layer of sand, as indicated at 2, is placed upon the bottom of each saggar, and the improved burning racks are placed upon said layer of sand at properly spaced intervals within the saggar from one end to the other.

These burning racks may be formed of clay, or other suitable material, and as shown in Figs. 2 and 3, may be of substantially channel shape, comprising the web bottom or body 70 portion 3, and the substantially triangular ribs 4, at the longitudinal edges thereof.

For the purpose of preventing accidental, lateral movement of the rack, upon the bottom of the saggar, the central portion of the under side of the rack may be longitudinally concave, as shown at 5, thus providing two spaced ribs 6, adapted to be imbedded in the sand, as indicated in Fig. 2.

Plates or the like, as indicated at 7, are then placed in rows upon each burning rack, the lower edges of the plates resting at spaced points on the edges of the triangular ribs 4, and the upper portions of the plates resting upon the triangular pins 8, the plates being entirely supported above the bottom of the saggar and out of contact with the sand.

Since the triangular ribs 4 are formed integrally upon the rack it will be seen that there can be no relative movement of these ribs to permit the plates to be displaced; and by providing the lower ribs 6 upon the rack the same may be imbedded in the sand and will prevent any lateral displacement of the rack due to the weight of the plates resting thereon.

As shown in Fig. 4, the rack 3^a may have the single triangular rib 4^a upon its upper surface, providing for a one point contact with the plate or other article to be burned,

the rack being otherwise the same as above described.

I claim:

1. In combination, a saggar, a layer of sand upon the bottom of the saggar, and a burning rack for said saggar upon the sand, means extending upward from and integral with the rack spacing the edge of a plate supported thereon entirely above the bottom of the saggar and out of contact with the sand, and means extending downward from the rack imbedded in the sand preventing lateral displacement of the rack in the sand.
2. In combination, a saggar, a layer of sand upon the bottom of the saggar, and a burning rack for said saggar upon the sand, the burning rack including a body portion, an upright rib integral with the body portion spacing the edge of a plate supported thereon entirely above the bottom of the saggar and out of contact with the sand, and means extending downward from the body portion imbedded in the sand preventing lateral displacement of the rack in the sand.
3. In combination, a saggar, a layer of sand upon the bottom of the saggar, and a burning rack for said saggar upon the sand, the burning rack including a body portion, an upright rib integral with the body portion at each longitudinal edge of the body portion spacing the edge of a plate supported thereon entirely above the bottom of the saggar and out of contact with the sand, and means extending downward from the rack imbedded in the sand preventing lateral displacement of the rack in the sand.
4. In combination, a saggar, a layer of sand upon the bottom of the saggar, and a burning rack for said saggar upon the sand, the burning rack including a body portion, a triangular rib extending upward from and integral with the body portion spacing the edge of a plate supported thereon entirely above the bottom of the saggar and out of contact with the sand, and means extending downward from the body portion imbedded in the sand preventing lateral displacement of the rack in the sand.

In testimony that I claim the above, I have hereunto subscribed my name.

BARTHOLOMEW H. GREENE.
